DESIGN FOR A SEMITRAILER AUTOMOBILE CARRIER

Clarence D. Gill, Baltimore, Md.

Application April 26, 1937, Serial No. 68,989

Term of patent 14 years

To all whom it may concern:

Be it known that I, Clarence D. Gill, a citizen of the United States of America, residing at Baltimore, in the county of Baltimore City, in the State of Maryland, have invented a new, original, and ornamental Design for a Semitrailer Automobile Carrier, of which the following is a specification, reference being had therein to the accompanying drawing, forming a part thereof, wherein:

automobile carrier showing my new design, shown to a somewhat reduced scale to that illustrated in Figures 2 and 3, respectively;

Figure 2 is a top plan view thereof;

I claim:

The ornamental design for a semitrailer automobile carrier substantially as shown.

CLARENCE D. GILL.
